CLAIM

The ornamental design for a tool suspension plate, as shown and described.

DESCRIPTION

FIG. 1 is a perspective view of a tool suspension plate showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plain view thereof;

FIG. 8 is an environmental, front view thereof; and,

FIG. 9 is a reduced scale, environmental front view thereof.

The broken line showing of a screw driver and a socket is for illustrative purposes only and forms no part of the claimed design.
